UNITED STATES PATENT OFFICE.

DALE O. COWEN, OF BATAVIA, OHIO.

COVER FOR WATER-CLOSET SEATS.

SPECIFICATION forming part of Letters Patent No. 296,141, dated April 1, 1884.

Application filed June 21, 1883. (No model.)

To all whom it may concern:

Be it known that I, DALE O. COWEN, of Batavia, in the county of Clermont and State of Ohio, have invented a new and useful Improvement in Covers for Water-Closet Seats, of which the following is a full, clear, and exact description.

The object of this invention is to provide a cheap and ready-made cover for the seats of water-closets and privies, which shall afford protection against the communication of disease in such of these necessary conveniences or articles as are used by different people or promiscuously—as, for instance, the water-closets or privies in places of public resort, including hotels, offices, factories, steamships, &c.

Reference is to be had to the accompanying drawings, forming a part of this specification, in which similar letters of reference indicate corresponding parts in all the figures.

Figure 1 represents a view in perspective of my improved seat sheet or cover as seen from its upper surface; Fig. 2, a perspective view of the same as seen from its under side, and Fig. 3 a section of the seat-sheet on the line $\alpha\alpha$ in Fig. 1.

A in the drawings is the seat-sheet, which may be made of cheap thin paper of a size to cover the top surface of the seat, or such portion thereof as is exposed to contact with the person. Said sheet has a hole, b , in it, corresponding with the hole in the seat of the water-closet. The sheet is designed to be used in connection with the seat as a seat-cover.

The edge adjacent to the hole of this sheet A is bent or turned downward to form a short funnel-like flange, c , of a shape to enter easily down within the hole in the seat of the closet, and so that said flange will cover or protect the margin or walls of the apertured portion of the seat from contact with the person of an individual using the seat, and will further serve to center or hold the seat-sheet in place.

These seat-sheets may be made of different sizes and shapes to suit different water-closets or privies and apertures in the seats thereof; but a few changes in these respects will suffice, inasmuch as it is not necessary that the sheets should be an exact fit, but only an approximate one to the seats they are designed to be used on.

I am aware that paper covers for a water-closet seat have been made with two circles of punctures and two flaps; also, that a sheet having the hole marked out by apertures and connecting strips, so that the piece will readily break away, has been used; but

What I claim as new and of my invention is—

As an improved article of manufacture, a water-closet-seat cover consisting of a sheet of paper, A , provided with a hole, b , having a downwardly-projecting flange, c , extending around said hole, the said flange being integral with the body of the sheet, as set forth.

DALE O. COWEN.
